UNITED STATES PATENT OFFICE.

GEORGE H. PERKINS AND GEORGE BROWN, OF PHILADELPHIA, PENNSYLVANIA, ASSIGNORS TO HANNIBAL MEAT COMPANY, (LIMITED.)

IMPROVEMENT IN CASES FOR SUPPORTING CANS.

Specification forming part of Letters Patent No. 211,041, dated December 17, 1878; Reissue No. 8,738, dated June 3, 1879; application filed February 8, 1879.

To all whom it may concern:

Be it known that we, GEORGE H. PERKINS and GEORGE BROWN, both of the city and county of Philadelphia, in the State of Pennsylvania, have invented a new and useful Improvement in Supporting Boiling-Cases for Cans, of which the following is a full, clear, and precise description, reference being had to the accompanying drawings, which form part hereof, and of which—

Figure 1 is a view, in perspective, of our improvement as suspended from the handling-crane and in readiness for immersion; Figs. 2 and 3, central longitudinal sections of two forms of construction of the case, exhibiting the cans in place; and Figs. 4 and 5, sectional details of two forms of opening in a lid, as hereinafter explained; Figs. 6 and 7, sectional details of two forms of extensions of the lid-openings, as hereinafter explained.

Similar letters of reference indicate corresponding parts.

Our invention is designed to be employed in connection with processes of preserving meats, &c., and hermetically sealing the same in cans; and consists, substantially, in the supporting boiling-case herein described and claimed, in which cans containing meat in the uncooked or partially-preserved state are placed, immersed in water, and boiled to the desired degree.

Heretofore, after the meat or other substance to be preserved has been placed in the can and the cap or cover sealed on, the can with its inclosed contents has been placed in boiling water and the whole boiled for a time, then removed from the boiling water, and the can punctured to allow of the escape of gases, resealed, and boiled again.

Frequently the pressure generated within the can has been sufficient to burst it outright or spread the seams, to the damage of the contents. To obviate this is the object of our invention.

Our supporting-case consists of a cell or of a series of cells or receptacles of the exact size of the cans to be subjected to the boiling process, arranged in any given series, and adapted to receive and support upon every side and

upon the bottom, and when the lid is employed against the top, of each can during the boiling, so as to guard against and prevent bursting of the cans.

In the drawings a case constructed to hold truncated-cone cans is represented.

It will, however, be understood that the cells may be formed to hold square, rectangular, cylindrical, or other shaped cans.

The case A is preferably made of iron, cast or wrought, and is constructed either as a series of cells, B B, of the desired size, united together, or else as a box divided off by partitions in such manner as to produce the cells.

In Fig. 3 is represented the first construction, in which it will be observed that the water or boiling medium has access to the space between the cells as well as above and below.

In Fig. 2 is represented the second construction.

The object being to support the can against the bulging pressure, it is requisite that the sides and bottom of the cells should be correspondent with those of the can, of whatever shape the latter may be, and fit closely against them. It is also requisite that a lid should, under certain conditions, be employed so as to inclose and press upon the tops of the cans also.

C is the lid, removably hinged to the case, the same consisting of a metal top adapted to bear upon or protect portions of the covers of each can, leaving, however, a space for the puncturing and resealing (and, when desired, for filling) of the can. The lid C is conveniently constructed as a flat cover, sufficient in its external dimensions to completely cover all the cells, and having a series of openings, C'', made to correspond with the cells, each opening being best made of an outline correspondent with the cap of the can-head, and of size sufficient either just to overlap the edges of the cap and so bear upon it, or of larger size, to permit the sealing on of the cap after the filling of the can within the cell, if desired.

The sides of the openings may be so constructed or arranged as to extend above the openings in the can and constitute chambers or vessels, or extensions C'', so to speak, of the

can, to the end that in the cooking process in the can ebullition or swelling of the contents can take place into the extensions without loss of material by overflow, the extensions being so formed as to facilitate the easy flow of the boiling material back into the can.

It is obvious that the lid must fit closely down upon the can, so that there shall be no escape of material between the lid and can-cover.

In Fig. 6 is represented a convenient method of forming the top-extensions by making a countersunk opening in a lid of the required thickness. In Fig. 7 is represented an extension formed by an embracing band or rim, D', erected upon a thin lid around an opening thereof.

The walls of the extension, however formed, are best inclined inwardly toward their base, so as to insure the effectual reflux of the material.

D D are locks to secure the lid in position.

It will be understood that the case can be employed either with or without its lid, according to circumstances, depending upon the thickness of the can-covers and the strength of their union with the body, upon the character of the contents, length of time requisite for boiling, and upon various other kindred conditions.

E E are chains or the like, by which the case can be handled with a crane. F F are drain-holes, provided to permit the escape of water. These holes may be of any desired number, shape, or size.

The case containing the filled cans (and with or without the cover) is readily immersed in the boiling medium and removed therefrom, effectuating a most material improvement over the old processes.

The cover, (when employed,) being best made in one piece, effects a material saving in the time necessarily consumed in the putting in and taking out of the cans over a construction embodying a series of smaller lids.

We are aware that sheet-metal boilers and

steamers and other kitchen utensils have been made in which cell-like receptacles are employed to receive cooking-vessels other than those hermetically sealed, in which cooking is to be done, and that these cell-like receptacles have more or less closely corresponded to the vessels they were intended to receive, and to any such devices we lay no claim, as it is of the essence of our invention that the cells should be of absolutely rigid material—such as cast-iron, in which there is no give—so that they aid the cans to resist any pressures which are generated within the cans, and which the cans themselves, alone and unsupported, are not strong enough to resist.

Having thus described our invention, we claim and desire to secure by Letters Patent of the United States—

1. A canning-cell formed of rigid material, as described, corresponding in shape to the sides and bottom of the can to be contained therein, and adapted to support said can upon sides and bottom against bursting-pressures, substantially as set forth.

2. A series of canning-cells formed of rigid material, as described, corresponding in shape to the sides and bottoms of the cans to be contained therein, and adapted to support said cans upon sides and bottoms against bursting-pressures, substantially as set forth.

3. The supporting boiling-case herein described, consisting of one or more cells formed of rigid material, and exactly corresponding in shape to the sides and bottom of the can or cans to be contained therein, in combination with a cover provided with one or more openings, and adapted to bear upon the tops of the cans and inclose them, substantially as and for the purposes set forth.

In testimony whereof we have hereunto set our hands this 28th day of January, A. D. 1879.

GEORGE H. PERKINS.

GEORGE BROWN.
